(57) **CLAIM**

The ornamental design for a utility bin, as shown and described.

DESCRIPTION

FIG. 1 is a top frontal perspective view of a utility bin according to my new design;

FIG. 2 is a bottom frontal perspective view thereof;

FIG. 3 is a front view thereof;

FIG. 4 is a back view thereof;

FIG. 5 is a right side view thereof;

FIG. 6 is a left side view thereof;

FIG. 7 is a bottom view thereof; and,

FIG. 8 is a top view thereof.

The ornamental design which is claimed is shown in solid lines in the drawings. Any broken lines in the drawings are for illustrative purposes only and form no part of the claimed design.
